UNITED STATES PATENT OFFICE.

FLORELLA L. KINSMAN, OF MAGOG, QUEBEC, CANADA.

CAR-HEATER.

SPECIFICATION forming part of Letters Patent No. 241,547, dated May 17, 1881.

Application filed January 31, 1881. (No model.)

To all whom it may concern:

Be it known that I, FLORELLA L. KINSMAN, of Magog, in the county of Stanstead and Province of Quebec, Canada, have invented certain new and useful Improvements in Car-Heaters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to certain improvements in car-heaters, the object of which is to allow air to be fed to the fire through the sides of the fuel-receptacle as well as through the grate; to crush or break the slag, clinkers, or slate which may accumulate in the fuel-receptacle; to provide for the thorough and constant feeding of air to the fire-chamber, whatever may be the direction of the moving car; to regulate the air-supply to the fire-chamber; to feed the air-supply to the fire-chamber evenly; and to regulate the air-supply or draft to the air-chamber.

In the annexed drawings, Figure 1, Sheet 1, is a side elevation of my improved car-heater with a section of a car-floor; Fig. 2 is a plan view of a section of the car-floor, showing the upper exposed portions of my car-heater. Fig. 3 is a bottom view of the heater. Fig. 4, Sheet 2, is a longitudinal vertical section of the car-heater on line xx of Fig. 2. Fig. 5 is an end view thereof. Fig. 6 is a transverse vertical section on line yy , Fig. 2. Fig. 7 is a detail view of the rack-bar and its spring. Fig. 8 is a detail of the crank-rod of the worm-gear wheel. Fig. 9 is a detail of the deflector, and Fig. 10 is a detail of the connection between the bar and shaft which operate the grate-bars.

Corresponding parts in the several figures are denoted by similar letters of reference.

Referring to the drawings, A A' represent a section of the floor and bottom of an ordinary passenger-car, secured to the stringers B B in the usual manner.

Fastened to and depending from the bottom A' of the car is a metal chamber, C, preferably of a rectangular form, inclosing a second chamber, D, smaller than the chamber C, to form an inclosed air-space between the two chambers. The combustion-chamber D is provided

with fingers d, suitably secured to and projecting from the walls of the chamber inwardly and downwardly, to form a tapering receptacle for the fuel, to permit the air to be fed to the fuel from the sides as well as the bottom of the receptacle. The combustion-chamber D is provided with a smoke exit or pipe, d'.

Resting in bearings secured to the chamber D are the grate-bars E, which form the bottom of the fuel-receptacle. The bearings of the grate-bars are arranged below and laterally beyond the bottom of the fuel-receptacle, by which clinkers, slag, ashes, &c., cannot jam or clog said bearings to interfere with the proper working of the grate-bars. These bars are T-shaped in cross-section and have depending arms, as shown.

Passing transversely through and connected to the depending arms of the grate-bars is a bar, e, the outer end of which works in a bearing-plate, e', secured to a bracket on the chamber C. One end of a shaft, F, has a bearing in the bracket of the plate e', and is loosely connected to the bar e by an arm. The other end passes up through the bottom and floor of the car, and receives a removable lever, f, to enable the operator to readily turn the rod F to give an oscillating movement to the bar e, and, in turn, oscillate the grate-bars to clear the latter of accumulated ashes. The object of making the grate-bars T-shaped in cross-section, and to give them an oscillating movement, is to break or crush the cinders, slag, or clinkers, as well as to remove or shake the ashes from the fuel-receptacle. The first-mentioned result is accomplished in the following manner, viz: Upon oscillating the grate-bars through the bar e and shaft F the width of the spaces between them will be increased, when the cinders or clinkers fill such increased space, and upon the return of the bars to their normal position the flanged bars have a shear cutting or crushing action upon the cinders or clinkers, thus reducing them to permit their easy passage between said grate-bars.

Pivoted in the bottom of the outer chamber, C, and below the grate-bars E, are the dampers G, arranged in two sets or series. It is obvious that they may be arranged differently, if desired. Each of the dampers is pivoted to a bar, g, the outer end of which has a bearing in the plate e', heretofore mentioned.

Engaging with the bar *g*, near its outer end, is a crank, *h*, of a shaft, *H*, which is supported in bearings secured to the chamber *C*. This shaft is provided with a worm-gear wheel, *I*, meshing with a worm, *i*, keyed or otherwise fastened to the shaft *i'*, which is supported in the bracket or extension of the chamber *C*, passes up through the floor, and receives a hand-wheel, *J*.

10 *G'* marks a deflector attached transversely to the chamber *D*, and located below the grate-bars *E* and between the two series of dampers.

Upon revolving the hand-wheel the worm will communicate motion to the worm-gear

15 wheel, which, in turn, through its shaft and crank, will operate the bar *g* to move the dampers *G*. By this means the operator can open or partially open the dampers, and hold them in such position that when the car is in motion

20 they will be presented obliquely toward the air, by which a strong current will be deflected into the combustion-chamber. It is apparent that this result can be brought about without regard to the direction in which the car is moving; and, further, the draft can be easily regulated in volume, while the position of the dampers will not be liable to change through the jarring motion of the car. The deflector is to

25 direct the air admitted through the first series of dampers into the forward part of the combustion-chamber to insure an even draft, and to prevent the current from being directed against the back part of the combustion-chamber, as it might be when the car is moving

30 rapidly.

35 *K* marks a magazine, which extends from the upper floor *A* down into the fuel-receptacle a suitable distance to make the heater self-feeding. The magazine is covered with a lid, *k*,

40 provided with a handle, to prevent the escape of gases from the combustion-chamber into the car. As a further protection, a pair of hinged doors, *k' k'*, may be placed over the magazine and its lid, as clearly shown in Fig. 1.

45 The outer or air chamber, *C*, is provided with a hinged door or damper, *c*, at the lower part of each end thereof, which opens upwardly. To each door is connected a rod, *l*, the upper extremity of which is connected to a rack-bar,

50 *L*, passing up through the bottom and floor, and provided with a series of teeth or serrations, *l'*, engaging with a plate, *M*, which surrounds the orifice made for the insertion of said rack-bar. A spring, *m*, (shown in Fig. 7,) presses

55 against the rack-bar *L*, to keep it in engagement with the plate *M*.

An air-space entirely surrounds the fuel-magazine, into which opens a flue, *N*, running between the floors, from which one or more small-

60 er flues, *n*, open into the car. The flues *n* may or may not be provided with a regulating-register.

When the car is in motion the door or damper on the end of the air-chamber nearest the forward part of the car is partially or fully opened, as desired, when the currents of air will be directed against and around the combustion-

70 chamber and up into the flue *N*, and be delivered in a heated state into the car. When the car is not in motion either one or both of the doors or dampers *c* may be opened to admit air to the air-chamber.

75 It will be observed that, if desired, registers for the flues *n* may be dispensed with, as the supply of heated air can be regulated by means of the doors or dampers *c*.

In warm weather the air-space may be filled with any suitable material which will allow free passage of air, but arrest dust, &c., by which the car may be readily and easily ventilated.

Having thus fully described my invention, what I claim, and desire to secure by Letters Patent, is—

1. In a pendent car-heater, the combination, 85 with the combustion-chamber *D*, provided with the fingers to form a tapering fire-pot, as shown, of a series of individual vibratory grate-bars arranged immediately below the tapering fire-pot, and having independent pivotal bearings 90 laterally beyond the bottom of said fire-pot, as and for the purpose set forth.

2. In a pendent car-heater, the combination, with the chamber *D*, provided with the fingers to form a tapering fire-pot, as shown, of a series 95 of individual vibratory grate-bars of *T* shape in cross-section, as shown, said bars arranged immediately below the tapering fire-pot, and each having pivotal bearings laterally beyond the bottom of said fire-pot, as and for the purposes set forth.

3. In a pendent car-heater, the combination, with the chamber *D*, provided with the fingers to form a tapering fire-pot, as shown, of a series 105 of individual vibratory grate-bars of *T* shape in cross-section, as shown, and arranged immediately below the tapering fire-pot, and having their pivotal bearings laterally beyond the bottom of said fire-pot, and means for vibrating said grate-bars, as and for the purpose set 110 forth.

4. The combination of a combustion-chamber, a series of grate-bars, *T*-shaped in both side and end elevation, the bar *e*, connecting said grate-bars together, and shaft *F*, loosely 115 connected to said bar, substantially as and for the purpose set forth.

5. In a pendent car-heater, the combination, with the chamber *D*, having the two sets of dampers *G G*, and the shaft *i'*, extending up 120 through the floor *A*, of suitable mechanism connecting with said dampers and shaft, by which the dampers may be operated from the interior of a car and be held in an open or partially-open position, for the purpose set forth. 125

6. The combination, with the chamber *D*, provided with the dampers *G G*, of the deflector *G'*, arranged with relation to said chamber and dampers, as shown, and for the purpose set forth.

7. In a pendent car-heater, the combination, with the chamber *D*, provided with the dampers *G*, as shown, of the damper-operating mechanism consisting of the bar *g*, shaft *H*, having 130

the crank and worm-gear wheel, and shaft i' , provided with the worm, as shown and described.

8. The combination, with a grated combustion-chamber provided with two or more dampers, the operating-bar g , shaft H, having crank and worm-gear wheel, and shaft i' , having the worm, of a deflector transversely arranged in said combustion-chamber below the grate-bars, about midway between said dampers, as and for the purpose set forth.

9. In a pendent car-heater, the combination, with the air-chamber having an exit-flue, and provided with a swinging door or damper at each end thereof, of the connecting-rods l , rack-

bars L, and plates M, all as shown and set forth, for the purposes described.

10. In a pendent car-heater, the combination, with the air-chamber having an exit-flue, and provided with a swinging damper at each end thereof, of the connecting-rods l , rack-bars L, plates M, and springs m , all as shown and described.

In testimony that I claim the foregoing I have hereunto set my hand this 30th day of October, 1880.
